UNITED STATES PATENT OFFICE.

MAHLON W. WAMBAUGH, OF ST. LOUIS, MISSOURI.

RAIL-JOINT AND TRACK-FASTENER.

1,274,221.

Specification of Letters Patent. Patented July 30, 1918.

Application filed May 28, 1918. Serial No. 237,119.

To all whom it may concern:

Be it known that I, MAHLON W. WAMBAUGH, a citizen of the United States, residing at St. Louis, in the State of Missouri, 5 have invented a new and useful Rail-Joint and Track-Fastener, of which the following is a specification.

The device forming the subject matter of this application is a rail joint and a track 10 fastening, of that general type shown in Patent No. 570,618, granted to me on the third day of November, 1896. In such a structure, sundry improvements are proposed, as will be manifest when the description 15 of the invention is read.

It may be stated, however, that, among other improvements, the invention contemplates novel means for holding the retainers in place on the ties, without resorting to the 20 use of bolts, screws and the like.

Another object of the invention is to provide an improved means for mounting the lugs which receive the ends of the truss rod, the lugs being independent of the angle bars.

Another object of the invention is to improve the construction of the strut which supports the intermediate portions of the truss rods.

It is within the province of the disclosure 30 to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that, within the scope of what is claimed, changes 35 in the precise embodiment of the invention shown can be made without departing from the spirit of the invention.

In the accompanying drawings:—

Figure 1 shows in side elevation, the meeting ends of a pair of rails, wherewith the device forming the subject matter of this invention has been assembled, parts appearing in section; Fig. 2 is a top plan of the structure shown in Fig. 1; Fig. 3 is a section taken approximately on the line 3—3 of Fig. 2; Fig. 4 is a fragmental top plan showing a portion of the base plate; Fig. 5 is a

top plan showing a modified form of the invention, a portion of the rail being broken away; and Fig. 6 is a section taken approximately on the line 6—6 of Fig. 5, parts being left in elevation.

Referring to Figs. 1 to 4 of the drawings, both inclusive, there is shown a rail road rail including a ball 1, a web 2 and a flange 3. The flanges 3 of a pair of rails, at the meeting ends thereof are supported on plates 4, which may be denominated "bases", since they may be either a part of a metal tie, or plates adapted to be mounted on wooden ties, since the specification does not purport to deal with any specific kind of tie, and the device hereinafter claimed may be used with many kinds of ties, and since, as I am well aware, no specific form of tie can be claimed 70 in the same application with a rail fastening.

On each side of the flange 3 of the rail, the bases 4 are provided with transverse ribs or serrations 5. The bases 4 are provided with elongated slots 6 and in the lower surfaces of the bases 4 enlarged recesses 7 are formed about the slots 6. Angle bars 8 coöperate with the web 2 of the rail in the well known manner, the upper edges of the 80 angle bars being inclined as shown at 9, as and for the purpose set forth in my prior patent above alluded to. The angle bars 8 are attached to the web 2 of the rail by bolts 10 or other securing devices. The angle bars 8 include outwardly extended base portions 11 coöperating with the flanges 3 of the rails. For a purpose to be set forth hereinafter, the base portions 11 of the angle bars 8 are cut 85 away at their ends, as shown at 12.

Retainers 14 in the form of plates, rest upon the bases 4 and overhang the flange 3 of the rail as shown at 15. It may now be stated that the bases 11 of the angle bars 8 are cut as shown at 12 to receive the part 95 15 of the retainers, and to permit the said parts to bear directly on the flanges 3 of the rails. The under surfaces of the retainers 14 are provided with transverse ribs or serrations 16 coöperating with the ribs 5 on the bases 4. The retainers 14 are provided with upstanding lugs 17 having notches 18 in their upper ends. L-shaped keepers 19, which are circular in cross section, are jour-

naled in the retainers 14. The shanks of the keepers 19 are adapted to move, for adjustment, in the slots 6 of the bases 4, the keepers including enlarged heads 20 received in 5 the enlarged recesses 7 of the bases 4. It will be seen that the construction is such that the keepers 19 may be rotated. Further, the keepers 19 along with the retainers 14 may be adjusted, longitudinally 10 of the members 4 owing to the presence of the slots 6 and the recesses 7 in said members.

The upper ends of the L-shaped keepers 19 overhang coacting wedges 21, the upper 15 wedges 21 coöperating with the upper ends of the keepers, and the lower wedges 21 bearing against the retainers 14. The coöperating faces of the wedges 21 are supplied with interengaged transverse teeth 22.

20 Truss rods 23 extend longitudinally of the rail 1 on opposite sides thereof and are received at their ends in the notches 18 which are formed in the lugs 17 on the retainers 14, the truss rods being terminally provided 25 with heads 24, which, coöperating with the lugs retain the truss rods 23 in the notches 18.

Struts are interposed between the intermediate portions of the truss rods 23 and the flanges 3 of the rails as disclosed in Figs. 30 1 and 3. These struts comprise, each, an upper wedge 25 bearing against the under surface of the flanges 3, and a lower wedge 26, the coacting faces of the wedges 25 and 26 being provided with interengaged trans- 35 verse teeth 27. The lower wedge 26 is supported on the intermediate portions of the truss rods 23 and is provided with seats 28 which receive the truss rods, the construction being such that the lower wedge 26 is held 40 against longitudinal movement, whereas the upper wedge 25 may be adjusted longitudinally. The wedges 25 and 26 coöperate when a right-line movement is imparted to the upper wedge 25 and do not operate by a 45 rotary movement.

In practical operation, the retainers 14 may be moved toward and away from each other, owing to the presence of the slots 6 and the recesses 7 in the members 4, this 50 operation permitting the part 15 of the retainers to coöperate with the flanges 3 of the rail. The wedges 21 may be moved longitudinally with respect to each other, the coöperating teeth 22 on the wedges serving to 55 hold them in adjusted positions. The wedges 21 coöperate with the upper ends of the keepers 19 and hold the retainers 14 on the members 4, the ribs 5 and 16 holding the retainers in place.

60 The lugs 17 carry the ends of the truss rods 23, and by moving the wedge 25 longitudinally, the wedge may be made to coöperate with the intermediate portions of the truss rods, and support the ends of the

rails, the teeth 27 holding the wedge 25 in 65 any position to which it may have been adjusted, the lower wedge 26 being held against longitudinal movement, because the seats 28 of the lower wedge receive the intermediate portions of the truss rods 23. 70

In Figs. 5 and 6, a modified form of the invention has been shown. In these figures, parts hereinbefore described have been designated by numerals previously used, with the suffix "a." In this form of the invention, the truss rods have been omitted, and one of the retainers denoted by the numeral 30, is held in place on the member 4^a, by securing devices 31 of any desired sort. 75

It will be understood that the keepers 19 may be rotated by striking the upper ends 80 of the keepers with a hammer or like tool, it being possible in this way to release the hold of the upper ends of the keepers on the wedges 21.

Having thus described the invention; what is claimed is:—

1. In a device of the class described, a base having elongated slots; a rail on the base; means for retaining one side of the rail on 90 the base; a retainer coöperating with the other side of the rail and supported on the base; superposed wedges mounted on the retainer; and keepers on opposite sides of the wedges, the keepers being journaled in 95 the retainer and overhanging the wedges, the keepers including heads retained in the slots of the base and adjustable therein toward and away from the rail.

2. In a device of the class described, bases; 100 rails thereon; fish plates connecting the rails; means for supporting the rails at one side; retainers on the bases and engaging the other side of each rail; means for attaching the retainers to the bases; a truss rod having its ends engaged with the retainers, independently of the fish plates; and a strut interposed between the intermediate portion of the truss rod and the rails. 105

3. A device of the class described, constructed as set forth in claim 2, and further characterized by the fact that the strut comprises superposed upper and lower wedges, the upper wedge having right-line movement with respect to the lower wedge, the 115 lower wedge having means for engaging the truss rod to hold the lower wedge against longitudinal movement.

4. A device constructed as set forth in claim 2 and further characterized by the fact that the means for attaching the retainers to the bases comprises keepers journaled in the 120 retainers and held in the bases; and a wedge interposed between the upper ends of the keepers and the retainers.

5. In a device of the class described, a base having elongated slots; a rail on the base; means for retaining one side of the

5 rail; a retainer coöperating with the other side of the rail and supported on the base; keepers journaled in the retainer; and a wedge interposed between the upper ends of the keepers and the retainer, the keepers lying on opposite sides of the wedge.

In testimony that I claim the foregoing as

my own, I have hereto affixed my signature in the presence of two witnesses.

MAHLON W. WAMBAUGH.
